UNITED STATES PATENT OFFICE.

SAMUEL M. COFFMAN, OF KANSAS CITY, MISSOURI, ASSIGNOR, BY MESNE ASSIGNMENTS, TO THE BUSHNELL MANUFACTURING COMPANY, A CORPORATION OF KANSAS.

VENDING MACHINE.

1,309,184.

Specification of Letters Patent. Patented July 8, 1919.

Application filed August 13, 1915. Serial No. 45,299.

To all whom it may concern:

Be it known that I, SAMUEL M. COFFMAN, a citizen of the United States, residing at Kansas City, in the county of Jackson and State of Missouri, have invented certain new and useful Improvements in Vending Machines, of which the following is a specification:

My invention relates to coin-controlled vending machines, and while susceptible to other purposes it is particularly adapted to vending postage stamps, theater tickets, railway tickets, etc., arranged in web form.

The invention embodies stamp selecting means to be controlled by coins of different denominations, so that a stamp, or stamps, equal in value to the inserted coin will be delivered to the purchaser at each operation of the machine.

20. The invention further provides for feeding all of the webs simultaneously to have stamps severed therefrom on the insertion of a coin of the proper denomination, and it also provides for feeding one web while 25 the companion webs are held stationary, so that stamps will not be severed from the latter when a coin of less denomination is inserted.

Other features of the invention will hereinafter appear, and in order that said invention may be fully understood, reference will now be made to the accompanying drawings, in which:

Figure 1 is a front elevation of the machine.

Fig. 2 is a vertical section of the case with the interior mechanism in elevation and in normal or locked position.

Fig. 3 is a side elevation partly in section 40 of the major portion of the interior mechanism removed from the case and unlocked preparatory to delivering stamps.

Fig. 4 is a side elevation of the interior mechanism unlocked and with the coin chute 45 and some of the adjacent parts removed.

Fig. 5 is a rear elevation of a bell-crank and adjacent parts.

Fig. 6 is a rear elevation partly in section, of the coin chute and adjacent mechanism.

Fig. 7 is a plan view partly in section of the interior mechanism removed from the case and one of the spools drawn backward

preparatory to loading it with a roll of stamps.

Fig. 8 is a vertical section on line VIII—VIII of Fig. 7, with a roll of stamps added.

Fig. 9 is an elevation, partly in section of a pawl and a ratchet wheel, and adjacent mechanism.

Fig. 10 is a section on line X—X of Fig. 9, with the pawl and ratchet wheel removed.

Fig. 11 is a broken side elevation of a latch and adjacent mechanism.

Fig. 12 is a vertical cross section of a rotary blade and its stop.

Fig. 13 is a rear elevation of part of the mechanism for simultaneously releasing all of the webs, so that they may be fed forwardly preparatory to having stamps severed therefrom.

Fig. 14 is a rear elevation of a part of the mechanism for releasing but one of the webs preparatory to advancing the same.

Fig. 15 is a horizontal section of two slide-ways and adjacent parts.

Fig. 16 is a broken vertical cross section, enlarged, on line XVI of Fig. 15.

Fig. 17 is a side elevation of the web feed rolls and adjacent parts.

Fig. 18 is a front elevation of a lever for simultaneously raising the upper feed rolls from the stamps, with adjacent parts in section.

Fig. 19 is a front elevation of the rotary blade and a stationary blade for severing the stamps from their webs.

Fig. 20 is a detail side elevation of a guide and a stop for the forward end of a web.

Fig. 21 is an inverted plan view of the stop with the guide removed.

Fig. 22 is a plan view of the guide and the stop with a lever for controlling said stop.

Fig. 23 is a broken inverted plan view, enlarged, of the forward portion of the web guide.

Fig. 24 is a vertical section on line XXIV of Fig. 22, with added means for securing the guide and the stop in place.

Fig. 25 is an enlarged detail of the forward end of a lock bar constituting a part of the invention.

In carrying out the invention, I employ a suitable case 1, provided at its front side 105 with a delivery opening 2, and at its upper

central portion with a coin slot 3 communicating with a depending coin guide 4, terminating immediately above the entrance to a coin chute 5, to which it is removably connected by a sleeve 5^a. Access can be had to the interior of the case through a rear door 1^a.

The lower end of the coin chute 5 is fixed to a plate 6, firmly secured upon a table 7, 10 removably arranged within the case 1 and carrying a frame 8. The top of the table 7 has a coin slot 9 registering with the lower end of the coin chute 5, to permit coins to drop into a tray 10 placed beneath said 15 table 7.

The passage of a coin through the slot 9 is arrested by a stop lever 11, fulcrumed intermediate its ends upon a transverse pin 12, fixed to the lower end of an arm 13 suspended from a pivot 14, rockably mounted in a bearing 15, Fig. 6, at the upper portion of the coin chute 5.

The stop lever 11 has a rear lateral extension 16, which normally rests upon the plate 6 beneath the rear portion of a lock bar 17, having a pin and slot connection 18 at its forward end to a crank 19, fixed upon one end of a rock shaft 20, journaled in the lower front portion of the frame 8 and provided at 30 its opposite end with an upwardly-extending stop 21, whose upper end normally extends into the path of a rotary blade 22, which coacts with a stationary blade 23, fixed to the upper front portion of the frame 8, in 35 severing the stamps from their webs when fed over said stationary blade 23. The rocking movement of stop 21 is limited by a strap 21^a secured to the adjacent side of the frame 8.

40 The crank 19 and the lock bar 17 are normally held in forward position by a bifurcated keeper 24, fixed to the rear top portion of the table 7 and having a shoulder 25 against which the rear end of said lock bar 45 is held by a coiled spring 17^a, until raised by the stop lever 11, when said lock bar is immediately drawn to the position disclosed by Fig. 3, by the spring 17^a. Upward movement of the rear end of the lock bar 17 is 50 limited by a transverse pin 26, extending through the keeper 24.

The rotary blade 22 is fixedly-mounted upon a drive shaft 27, which projects through the front side of the case 1 and is 55 journaled in bearings 28, at the upper portion of the frame 8. Said drive shaft 27 may be actuated either manually or by a suitable motor (not shown). In the present instance, I have shown a crank handle 29 fixed to the forward end of the shaft, so that the same may be manually operated. The drive shaft 27 primarily controls the web feed rolls, the stop lever 11, and certain selecting mechanism, as will hereinafter 60 appear.

65 30 designates a cam fixed upon the drive shaft 27 and bearing against the arm 13, which is swung outward at each revolution of said cam 30 and moves the stop lever 11 laterally from over the coin slot 9, so that a 70 coin may drop therethrough. The arm 13 is held in engagement with the cam 30, by a coiled spring 32. The drive shaft 27 is held from backward rotation by a pawl 33 and a ratchet wheel 34, which latter is 75 fixedly-mounted upon the rear end of said shaft, while the pawl 33 is pivotally mounted at the rear end of the frame 8. The shaft 27 is further secured from backward rotation by the free end of the rotary blade 22 springing beneath a projection 22^a, on the adjacent side of the frame 8.

80 The ratchet wheel 34 is provided with a wrist pin 35, which projects into the grooved portion of a lever 36, Figs. 7 and 9, fulcrumed at 37 and pivotally connected at its free end to a depending link 38, pivoted at its lower end to a bell-crank 39, fulcrumed at 40 and pivotally connected at its lower end to a plunger 41, extending forwardly 90 through slots 42 and 43, in the coin chute 5, Fig. 3. The plunger 41 is normally held against the bottom of the slot 42, by a coiled spring 44 connected to the rear end of said plunger and a pin 45, carried by one arm of the bell-crank 39. The two arms of the bell-crank 39 are not rigidly connected as is customary, but are yieldingly retained in normal relation to each other by a coiled spring 46, connected at its ends to said arms, 100 one of which has a pin 39^a to bear against the companion arm and limit the spreading apart of the free ends of the arms.

105 The plunger 41 constitutes an important feature of the stamp selecting mechanism, which embodies bell-cranks 47, 48 and 49, Fig. 4, a rock frame 50, feed rolls 51 and 52, and fingers 53. The rock frame 50 is connected to the bell cranks 47 and 49, through the intermediacy of connecting rods 54 and 110 55, having pin-and-slot connections 56 and 57, respectively, with the adjacent side of the rock frame 50, Figs. 4 and 13. The rock frame is normally held in raised position by a flat spring 50^a.

115 Bell-cranks 47, 48 and 49, are fulcrumed upon a common pivot 58 and provided at their lower ends with superimposed lateral extensions 59, 60 and 61, respectively, which normally close the slot 43, against the edge 120 of which they are yieldingly held by a spring 62, secured to the front side of the coin chute 5 and tensioned by a set screw 63. The lateral extensions 59, 60 and 61 have V-shaped grooves presented to the pointed end 125 of the plunger 41, to prevent said end from slipping off any of said extensions when pushed forward as shown on Figs. 3 and 4.

130 The rock frame 50 has presser feet 64, 65 and 66, Fig. 13, to act on levers 67, 68 and

69. Fig. 7, fulcrumed in housings 70, 71 and 72, respectively, each of which is provided with a number of the fingers 53 for entering the perforations in the stamp webs. The 5 bell-crank 48 actuates a presser rod 48^a, extending through a guide 48^b, and adapted to actuate the lever 69. The forward ends of the levers 67, 68 and 69, extend through their respective housings, Figs. 21 and 24, and beneath the fingers 53 therein to raise said fingers from the perforations in the stamp webs, so that the same may be fed forward by the rolls 51 and 52 preparatory to having stamps severed therefrom.

15 The housings 70, 71 and 72 are superimposed on web guides 73, 74 and 75, respectively, and have perforations 76, Figs. 23 and 24, for the passage of the downwardly bent forward ends of the fingers 53. The 20 housings and the web guides are removably secured upon a transverse bar 77 of the frame 8, by set screws 78 threaded through an upper transverse bar 79 and provided with lock nuts 80, to secure them from accidental displacement. Each web guide has a lug 74^a, for abutment against the rear edge of the bar 77, as an aid in properly adjusting the guides upon said bar.

The feed rolls 51, which run idle on the 30 feed roll 52, are journaled in rock frames 81, fulcrumed upon a pin 82 extending through the upper portion of the frame 8, and their forward ends are yieldingly depressed by coil springs 83 to hold the feed 35 rolls 51 in frictional engagement with the feed roll 52, so that they will be rotated thereby and coact therewith in advancing the webs. The springs 83 are tensioned by set screws 84 threaded in a transverse bar 40 85, at the upper portion of the frame 8. The feed roll 52 is mounted upon a shaft 86, journaled in the frame 8 and provided at one end with a bevel gear 86^a which is driven by a bevel gear 87 fixedly-mounted upon the 45 drive shaft 27.

When the parts are at rest the feed rolls 51 are held in raised position by a U-shaped lever 88, from the stamp webs to prevent the mucilage thereon from sticking to the roll 50 52 in damp weather. Said lever 88 is fulcrumed upon the pin 82, and its rear transverse portion 89 bears upon the rear portions of the rock frames 81 for the purpose of depressing the same and raising the feed rolls 55 51 when the laterally projecting end 90 of said lever 88, is held in raised position by a cam 91, projecting from the drive shaft 27. 92 designates a latch mounted at one end upon a pivot 93 and curved upward at its 60 opposite end to rest upon a pin 94, carried by a trip lever 95 fulcrumed at 96 and having a curved upper terminal 97 arranged in the path of the cam 30, which moves said trip lever 95 to the dotted position, Fig. 4, 65 at each revolution of the shaft 27. The

lower end of the trip lever 95 is pivoted to one end of a connecting rod 99, pivoted at its opposite end to the crank 19 to advance the same to the dotted position, Fig. 4, to rock the stop 21 into the path of the rotary blade 22 and draw the lock bar 17 against the shoulder 25, to lock said stop 21 in the path of said rotary blade 22. When the lock bar 17 is raised above the shoulder 25 by the stop lever 11, Fig. 3, said lock bar 17, the 70 crank 19, and the trip lever 95 are drawn to the full line positions, Fig. 4, through the intermediary of the coiled spring 17^a.

The latch 92 is normally held upon the pin 94 by a coiled spring 102, attached at one end to said latch and at its opposite end to a pin 103, and said latch 92 has a notch 104 to receive and hold the lateral extension 61 on the lever 49, when the same is swung back by the plunger 41 to the position disclosed by Fig. 3. The stamp webs are carried on spools 105, 106, and 107, each of which has a fixed flange 108 which co-operates in holding the stamp web rolls upon said spools.

The spools 105 and 106 are removably mounted upon a common shaft 109, fixed to a slide 110, mounted in a slideway 111 at one side of the frame 8. The spool 107 is removably mounted upon a shaft 112, fixed to a slide 113, provided with a flange 108 and mounted in a slideway 114, at the opposite side of the frame 8. Movement of the slides in their respective slideways is limited by stop pins 115, secured to the ends of said slides, Fig. 7. When a spool is to be loaded with a roll of stamps, its slideway is drawn back to the position disclosed by the slide 113, Figs. 7 and 15, so that said spool can be removed from its shaft and readily inserted 105 in an opening in the center of the roll.

When the stamps are severed from the webs by the blades, they are conducted to the delivery opening 2, in the case 1, by an apron 116, suspended just beneath the stationary blade 23. The apron 116 is mounted on a pivot 117, so that its free end may be pushed out of the path of the rotary blade 22, as the same rotates.

Assuming that the spools 105 and 106 are 115 provided with rolls of 2¢ stamps, and the spool 107 is provided with a roll of 1¢ stamps, the manner of dispensing said stamps is as follows: On dropping a dime A, through the coin slot 3, it descends upon the 120 underlying end of the stop-lever 11 and tips the same to the position disclosed by Fig. 3, causing its lateral extension 16 to raise the lock-bar 17 out of engagement with the shoulder 25, whereupon said lock-bar is immediately drawn backward over said shoulder by the spring 17^a. As the lock-bar 17 moves backward it swings the crank 19 therewith, causing it to rock the shaft 20 and swing the stop 21 out of the path of the 130

rotary blade 22. The crank handle 29 is then actuated to rotate the blade 22 and the feed rollers 51 and 52, so that the stamps of all three webs may be fed forward after 5 the fingers 53 have been raised from the perforations in said webs. Said fingers 53 are raised by the depression of the rear ends of the levers 67, 68 and 69 through the intermediary of the presser feet 64, 65 and 66, 10 the rock-frame 50 of which is drawn downward through the intermediary of the bell-crank 49, the lateral extension 61 of which is pushed forward into the notch 104 of the latch 92 by the plunger 41, Fig. 3, the forward end of which is guided into engagement with said lateral extension 61 by the upper edge of the arrested dime A. The plunger 41 is advanced to the forward position, Fig. 3, through the intermediary of the bell-crank 39, the link 38, the lever 36, the wrist pin 35, and the ratchet wheel 34. About the time the plunger 41 reaches the end of its forward stroke, the cam projection 31 engages the arm 13 and swings it 15 laterally until the stop-lever 11 is carried outward from beneath the dime, which then drops through the slot 9 and into the tray 10. When the plunger 41 recedes the extension 61 is still held in forward position, 20 Fig. 3, by the latch 92, so that the fingers 53 of the guides 73 to 75, inclusive, are held in raised position until each web is advanced almost the length of two stamps, at which 25 time said latch 92 is raised out of engagement with the extension 61 by the pin 94 on the lever 95, which is rocked to the dotted position, Fig. 4, by the cam 30. When this occurs the rock-frame 50 is immediately 30 raised by the spring 50^a and permits the fingers 53 to drop and engage the second row 35 of perforations in the webs as the latter are advanced by the feed rolls. Just as the shaft 27 begins its revolution, the cam 91 passes from beneath the projection 90 of the 40 lever 38, and allows the latter to relieve the pressure on the rock-frames 51, so that the upper feed rolls 51 can be forced downward by the springs 83 upon the underlying stamp 45 webs and goad with the feed roll 52 in feeding the stamps forward. As the upper end 50 of the trip lever 95 is swung backward by the cam projection 31, the lower end of said lever swings forward, and through the intermediary of the connection bar 99 swings 55 the crank 19 forward until the lock-bar 17 is drawn into engagement with the shoulder 25. As the crank 19 swings forward it carries the stop 21 therewith, so that the same will be in the path of and stop the blade 22 60 when it has completed the revolution.

If a nickel B, is inserted in the machine the above operation is repeated, excepting that said nickel being of greater diameter than the dime, raises the point of the 65 plunger 41 into engagement with the lateral

extension 59, which on being swung forward by said plunger 41 to the position disclosed by Fig. 4, is not engaged by the latch 92 and consequently the rock-frame 50 is permitted to swing upward and allow the 70 fingers 53 to drop and engage the first row of perforations in the webs, so that the same will be forced forward the length of but one stamp preparatory to being severed by the blades. 75

When a penny C, is inserted its upper edge guides the plunger 41 into engagement with the intermediate extension 60, which is forced forward, and through the intermediary of the presser rod 48^a depresses the 80 lever 69 only, so that only the fingers 53, engaging the penny web will be raised from the perforations thereof, and allow said web to be fed forward while the two companion webs are held stationary by their respective 85 fingers 53.

While the foregoing arrangement of the stamps does not allow a profit to the vendor, it is apparent that a profit of one cent can be realized on each nickel's worth sold by 90 substituting another penny web for one of the 2¢ webs, so that on the insertion of a nickel one 2¢ and two 1¢ stamps will be delivered.

Having thus described my invention, what I claim and desire to secure by Letters Patent, is:

1. In a vending machine, a chute, a stop to arrest the passage of a coin through said chute, a shaft released by said stop, web-selecting mechanism actuated by said shaft, and rotary feeding means for advancing the selected web. 100
2. In a vending machine, a chute, a stop to arrest the passage of a coin through said chute, a shaft released by said stop, web-selecting mechanism actuated by said shaft, feeding means for advancing the selected web, and means for severing the web. 105
3. In a vending machine, a chute, a stop to arrest the passage of a coin through said chute, a shaft released by said stop, web-selecting mechanism actuated by said shaft, feeding means for advancing the selected web, means for severing the web, and means 110 for shifting the stop out of the path of the arrested coin.
4. In a vending machine, a chute, a stop to arrest the passage of a coin through said chute, a shaft released by said stop, web-selecting mechanism actuated by said shaft, feeding means for advancing the selected web, means for severing the web, means for shifting the stop out of the path of the arrested coin, and means for restoring the 115 stop to normal position after the passage of the coin. 120
5. In a vending machine, a chute, a stop to arrest the passage of a coin through said chute, a shaft released by said stop, web- 125

- selecting mechanism actuated by said shaft, feeding means for advancing the selected web, means for severing the web, and means for delivering the severed portion of the web.
6. In a vending machine, a chute, a stop to arrest the passage of a coin through said chute, a shaft released by said stop, web-selecting mechanism actuated by said shaft, 10 web-holding means released from the selected web by said web selecting mechanism, and feeding means for advancing the selected web.
7. In a vending machine, a chute, a stop to arrest the passage of a coin through said chute, web-selecting mechanism, feeding means for advancing the selected web, means for severing the web, means for shifting the stop out of the path of the arrested coin, 20 and a drive shaft released by the stop to actuate the web-selecting mechanism, the feeding means, and the stop shifting means.
8. In a vending machine, a chute, a fulcrumed stop to arrest the passage of a coin through said chute, a shaft released by said stop, web-selecting mechanism actuated by said shaft, feeding means for advancing the selected web, and means for severing the web.
9. In a vending machine, a chute, a stop to arrest the passage of a coin through said chute, a shaft released by said stop, web-selecting mechanism actuated by said shaft, an arm carrying said stop, a cam to cause 35 said arm to shift the stop out of the path of the arrested coin, and feeding means for advancing the selected web.
10. In a vending machine, a chute, a stop to arrest the passage of a coin through said chute, a shaft released by said stop, web-selecting mechanism actuated by said shaft, an arm upon which said stop is operably mounted, a cam to move said arm in one direction to shift the stop out of the path of 45 the arrested coin, resilient means to restore the arm to normal position, and feeding means for advancing the selected web.
11. In a vending machine, a chute, a stop to arrest the passage of a coin through said chute, a shaft released by said stop, selecting mechanism actuated by said shaft and including a member guided by the periphery of the coin in the chute.
12. In a vending machine, a chute for coins 55 of different denominations, means to arrest the passage of the coins through said chute, a plunger guided by the periphery of each coin in contact with said arresting means, and means selected by said plunger to release articles to be vended.
13. In a vending machine, a chute for coins of different denominations, means to arrest the passage of the coins through said chute, a plunger guided by the periphery of 65 each coin in contact with said arresting means, bell-cranks selected by said plunger, and means actuated by said bell-cranks to release articles to be vended.
14. In a vending machine, a chute for coins of different denominations, means to 70 arrest the passage of the coins through said chute, a plunger guided by the periphery of each coin in contact with said arresting means, bell-cranks selected by said plunger, means actuated by said bell-cranks to release articles to be vended, and web-holding fingers controlled by said bell-cranks.
15. In a vending machine, a chute for coins of different denominations, means to 80 arrest the passage of the coins through said chute, a plunger guided by the periphery of each coin in contact with said arresting means, an element selected by said plunger, web-holding means released by said element, means for advancing the released webs, and 85 a latch to arrest said element at a point in its movement to prolong the advancement of the webs.
16. In a vending machine, a chute for coins of different denominations, means to 90 arrest the passage of the coins through said chute, a plunger guided by the periphery of each coin in contact with said arresting means, an element selected by said plunger, web-holding means released by said element, 95 means for advancing the released webs, a latch to arrest said element at a point in its movement to prolong the advancement of the webs, and means to release said latch from the element.
17. In a vending machine, a chute for coins of different denominations, means to 100 arrest the passage of the coins through said chute, a plunger guided by the periphery of each coin in contact with said arresting means, an element selected by said plunger, web-holding means released by said element, means for advancing the released webs, a latch to arrest said element at a point in its movement to prolong the advancement of 105 the webs, a lever to release said latch from the element, and a cam to actuate said lever.
18. In a vending machine, a chute for coins of different denominations, means to arrest the passage of the coins through said chute, a plunger guided by the periphery of each coin in contact with said arresting means, a bell-crank for controlling said plunger having two arms capable of independent movement, resilient means to hold 110 said arms in normal relation to each other, actuating means connected to one of said arms, and means selected by said plunger to release articles to be vended.
19. In a vending machine, a chute for 125 coins of different denominations, means to arrest the passage of the coins through said chute, a plunger guided by the periphery of each coin in contact with said arresting means, members having superimposed ex- 130

tensions to be selected and actuated by said plunger, and means controlled by said members to release articles to be vended.

20. In a vending machine, a chute, a stop to arrest the passage of a coin through said chute, a lock bar released by said stop, a rotary blade, a stationary blade to coact with said rotary blade, and a stop for said rotary blade which operates in unison with 10 the lock bar.

21. In a vending machine, a chute, a stop to arrest the passage of a coin through said

chute, a lock bar released by said stop, a blade, a rotary shaft carrying said blade, feed rolls geared to said shaft, and a stop 15 for said blade which operates in unison with the lock bar.

In testimony whereof I affix my signature, in the presence of two witnesses.

SAMUEL M. COFFMAN.
